CLAIM

The ornamental design for a sports board, as shown and described.

DESCRIPTION

FIG. 1 shows a perspective view of a sports board;

FIG. 2 shows a side elevational view of the sports board shown in FIG. 1;

FIG. 3 shows a front elevational view of the sports board shown in FIG. 1, the rear elevational view being a mirror image thereof;

FIG. 4 shows a top plan view of the sports board shown in FIG. 1; and,

FIG. 5 shows a bottom plan view of the sports board shown in FIG. 1.
